Inventor.

Albert Edward Hayden,
by R. H. Eddy atty.

UNITED STATES PATENT OFFICE.

ALBERT E. HAYDEN, OF HOLYOKE, MASSACHUSETTS, ASSIGNEE, BY MESNE ASSIGNMENTS, TO HIMSELF AND EUGENE CLIFFORD HAYDEN, OF SAME PLACE.

SHIRT.

SPECIFICATION forming part of Letters Patent No. 284,634, dated September 11, 1883.

Application filed May 8, 1883. (No model.)

To all whom it may concern:

Be it known that I, ALBERT EDWARD HAYDEN, of Holyoke, in the county of Hampden, of the Commonwealth of Massachusetts, have 5 invented a new and useful Improvement in Shirts; and I do hereby declare the same to be described in the following specification and represented in the accompanying drawings, of which—

- 10 Figure 1 is a front view of a shirt provided with my invention, the nature of which is defined in the claims hereinafter presented. Fig. 2 is a view of the shirt-front as it appears without the folded and slotted bosom. Fig. 3 is a 15 transverse section of such bosom. Fig. 4 is a transverse section of the shirt-front and the folded bosom. Fig. 5 is a representation of the shirt-bosom as open or folded back, so as to show the fly and buttons.
- 20 My invention relates particularly to what are termed "wheelmen's shirts;" and it consists in the mode of making the bosoms and the fronts of such shirts.

The shirt-front is simply open from the 25 collar or neck band down the middle of such front to the waist, or thereabout, such being as shown in Fig. 2, in which the opening in the front A is represented at *a* as extending downward from the collar *b* a suitable distance.

30 The bosom B is formed of a single piece of cloth or material separate from the shirt-front, and preparatory to being laid thereon and stitched thereto is folded, slit, and provided with buttons and a buttoning-fly—that is to say, it is folded widthwise in manner as shown in transverse section in Fig. 3, in which the front is shown as folded at *f* and *g*, so as to have at and down its middle a broad plait, *p*.

35 It is next folded at *e*, directly underneath the middle of such plait *p*, and extended laterally beyond the bend *f* a suitable distance to *d*, where it is again folded back to *c*. Next the cloth is folded outwardly at *h* a short distance 40 from the bend *g*, and again inwardly at *i* at a distance, *g i*, equal to *f d*, all being as repre-

sented. This having been done, the bosom is to be slit in the bend *e*, from the upper end thereof about two-thirds down the length of the bosom, and there is to be inserted between the parts *d e* and *e f*, and fixed to the latter a buttoning-fly, *l*, to extend from the upper end of the bosom down to the lower end of the slit, the said buttoning-fly being provided with button-holes to engage with buttons *m* 55 sewed on the part *d e*. The bosom having been so prepared is to be laid on the shirt-front so as to have the plait *p* at its middle directly over the opening at the middle of such shirt-front, which having been done, the 60 folds of the bosom are to be sewed together by rows of stitches arranged in them and the shirt-front in manner as shown at *n n*, *o o*, *q q*, *r r*, and *s* in Figs. 1 and 4. The bosom is also at its lower end to be stitched to the shirt-front, while at its upper end such bosom, with the exception of the part thereof which laps on the fly, is to be stitched to the shirt-front or the collar. In the bosom, along the middle of it, I usually have two rows of eyelets to receive a cord laced through them and eyelets in the collar or neck band.

I am aware that a shirt has been patented which has a bosom somewhat like the overlapping portion of the bosom herein shown.

75 I claim—

1. In a shirt, the bosom B, having the folds *d e f g i* and slit in the fold *e*, as set forth.
2. In a shirt, the bosom B, having the folds *d e f g i* and slit in the fold *e*, and provided with the separable fastenings or a buttoning-fly and buttons, arranged in and secured to opposite parts of such fold, as set forth.
3. The shirt A, having the slit *a* in front, in combination with the bosom B, having the folds *d e f g i* and slit in the fold *e*, such bosom being sewed to the shirt-front, as set forth and described.

85 ALBERT EDWARD HAYDEN.
